[57] **CLAIM**

The ornamental design for a housing for a hand-held electronic game, as shown and described.

DESCRIPTION

FIG. 1 is a top, front and right perspective view of a housing for a hand-held electronic game showing my new design;

FIG. 2 is a top plan view thereof;

FIG. 3 is a front elevational view thereof; the rear elevational view being a mirror image thereof;

FIG. 4 is a bottom plan view thereof; and,

FIG. 5 is a right side elevational view thereof; the left side elevational view being a mirror image thereof.

FIGS. 2-5 are drawn in small scale.
